UNITED STATES PATENT OFFICE.

GEORGE W. HOLMAN, OF DES PLAINES, ILLINOIS, ASSIGNOR TO ROYAL ENAMELING & MANUFACTURING COMPANY, OF CHICAGO, ILLINOIS, A CORPORATION OF ILLINOIS.

DESIGN FOR A TABLE-TOP.

51,594.

Specification for Design.

Patented Dec. 18, 1917.

Application filed March 17, 1917. Serial No. 155,621. Term of patent 14 years.

To all whom it may concern:

Be it known that I, GEORGE W. HOLMAN, a citizen of the United States, residing at Des Plaines, in the county of Cook and State of Illinois, have invented a new, original, and ornamental Design for a Table-Top, of which the following is a specification, reference being had to the accompanying drawing, forming part thereof.

Figure 1 is a perspective view of a table top showing my new design, and

Fig. 2 is a partial sectional view through the table top.

I claim:

The ornamental design for a table top, as shown.

GEO. W. HOLMAN.
